CLAIM

The ornamental design for a lockable wagering chip container, as shown.

DESCRIPTION

FIG. 1 is a top perspective view of a lockable wagering chip container showing my new design;

FIG. 2 is a top plan view thereof;

FIG. 3 is a side elevation view thereof; and,

FIG. 4 is an end elevation view thereof.

The broken line showing a key is provided for the purposes of illustrating environmental structure and forms no part of the claimed design.
